CLAIM

The ornamental design for a post-surgical compression garment, as shown and described.

DESCRIPTION

This application is related to co-pending related regular U.S. patent application Ser. No. 18/337,946 entitled Post-Surgical Compression Garment and filed Jun. 20, 2023. This application is also related to co-pending related U.S. design patent application Ser. No. 29/878,336 entitled Post-Surgical Compression Garment and filed Jun. 20, 2023.

FIG. 1 is a front right-side perspective view of the compression garment of the present invention.

FIG. 2 is a rear right-side perspective view thereof.

FIG. 3 is a front view thereof; and,

FIG. 4 is a rear view thereof.

The thinner dashed broken lines show portions of the post-surgical compression garment which form no part of the claimed design. The thicker broken lines in the figures represent stitching and form part of the claimed design.
